US0D1084615S

(12) United States Design Patent (10) Patent No.: US D1,084,615 S
(45) Date of Patent: * Jul. 22, 2025

(54) SANDAL

(71) Applicant: Fuzhou HanGeYi Business Management Co., Ltd., Fuzhou (CN)

(72) Inventor: Delin Liu, Fuzhou (CN)

() Term: 15 Years

(21) Appl. No.: 29/943,431

(22) Filed: May 21, 2024

(51) LOC (15) Cl. 02-04
(52) U.S. Cl.

USPC D2/916

(58) Field of Classification Search

(57) CLAIM

The ornamental design for a sandal, as shown and described.

DESCRIPTION

FIG. 1 is a perspective view of a sandal showing the new design;

FIG. 2 is another perspective view thereof;

FIG. 3 is a left-side view thereof;

FIG. 4 is a right-side view thereof;

FIG. 5 is a top view thereof;

FIG. 6 is a bottom view thereof;

FIG. 7 is a front view thereof; and,

FIG. 8 is a back view thereof.

The broken lines depict portions of the sandal that form no part of the claimed design.

1 Claim, 8 Drawing Sheets
